UNITED STATES PATENT OFFICE.

OTIS M. KENNEDY, OF PHILADELPHIA, PENNSYLVANIA.

DUST-CLEANING SUCTION-PUMP.

1,401,789.

Specification of Letters Patent. Patented Dec. 27, 1921.

Application filed March 28, 1919. Serial No. 285,790.

To all whom it may concern:

Be it known that I, OTIS M. KENNEDY, a citizen of the United States, residing in the city of Philadelphia, State of Pennsylvania, have invented certain new and useful Improvements in Dust-Cleaning Suction-Pumps, of which the following is a full, clear, and exact description, reference being had to the accompanying drawings, forming 10 a part of this specification.

My invention has for its object to provide a comparatively small and manually operated suction pump especially adapted to clean the dust which commonly enters 15 very small openings to tubular passages or ducts, such as the openings of the air passages of the tracker bar of a player piano, and to that end requires very close contact of the suction opening of the device 20 with the terminal surface of the opening to be cleaned.

To operate effectively it should be a guided suction contact as the tracker bar has a rounded surface perforated by a horizontal series of duct openings. It is essential 25 to the proper operation of such a dust-cleaning suction device, that additional means be provided to discharge the dust drawn into it, and which should be operated by the same actuating means which 30 draws the dust into the barrel or cylinder, but in successively alternating and reversed order.

For the performance of these several 35 functions my invention consists of the several coördinated elements, combined and operating as hereinafter described and comprising the usual cylinder, piston, piston rod and operating handle of a small hand 40 pump, with a yieldable contact cap on the head end of the cylinder, the cap being either wholly of rubber or supplied with a yieldable contact surface, the cap being axially apertured. Valvular means normally 45 close this aperture, which is opened on the suction stroke. To impart to the contact cap a guiding function it is provided on its face with a rounded groove or channel, extending from side to side, preferably adding 50 an elongated slot at the base of and intermediate the length of the groove. To discharge the dust sucked into the cylinder, a valvular device is mounted on the periphery of the cylinder, communicating directly 55 with the interior of the cylinder, normally

closed, and operable only on the return stroke of the piston. My invention includes a specific and preferable construction of the dust-discharging valvular means, constructed and operating on that principle and comprising, in combination with the check valve as before stated, a spring-controlled tubular body closed at one end, and with peripheral openings therein, slidingly mounted on a tubular member communicat- 60 ing at one end with said sliding member and at its other end communicating directly with the interior of the cylinder body.

The device is simple and cheaply constructed, and most efficient in operation, the 70 rounded groove or channel on the face of the contact cap operating to maintain the axially disposed suction aperture therein in alignment with the horizontally arranged line of ducts or openings in the periphery 75 of the rounded tracker bar, without guidance by the operator, while the resilient or yielding face of the contact cap maintains, with the slightest pressure from the operator, so close a contact as to create a substantial 80 vacuum back of it and in the barrel between the check valve and the piston, resulting in easily and effectively sucking into the pump barrel, all dust which has entered through the perforations of the tracker bar 85 and accumulated within the ducts and connecting tubes leading therefrom to the pneumatic devices of the instrument, and this without lifting the device from contact with the tracker bar until it has passed over the 90 entire row of perforations or ducts therein, which are exceedingly small in area and frequently number as many as 88 in a bar of some 18 inches in length.

In the drawings illustrating my invention, Figure 1 is an elevation and Fig. 2 a vertical section, of the simpler form of my device, and Fig. 3 an elevation, Fig. 4 a vertical section, and Fig. 5 top end view, of the modified and extended form of the 95 invention.

Referring now to said drawings, the cylinder is indicated at 1, the plug end thereof, having the usual air outlets, is indicated at 2, the piston rod at 3, its operating end 100 at 4, and the piston at 5. In the form shown in Figs. 1 and 2 of Sheet 1 the head end of the cylinder is closed save that it is provided with a terminal nipple 6 which is centrally apertured at 7. The elastic head or contact 105

cap 8 which in this embodiment of the invention is a molded block of comparatively soft rubber, is centrally apertured at 9 to conform in shape with and fit tightly over the nipple 6 and is additionally secured in place thereon by shellac or cement 10, between its base and the flat annular surface around the nipple. Proceeding concentrically from the aperture 9, and alining with the aperture 7 in the nipple, the elastic head is provided with a communicating opening 11 extending to the contact end 12 which may be flat as shown in Fig. 2; but in the modification shown in Figs. 3, 4 and 5 it is provided with a shallow rounded channel or concavity such as indicated at 18 for making closer contact with a rounded surface, and the concavity lined with felt or soft wash leather also, if preferred, as shown in such modified form of the invention about to be described.

Referring now to Figs. 3, 4 and 5, the cylinder, piston, piston rod and operating end of the latter, are the same as in the other form. The cylinder may have a grasping part 13 sleeved over it, if preferred.

In this form the cylinder end is open and is provided with an annular flange 14 on which is mounted the contact head or cap 8', but in this case the body head 8' may be rigid, say of wood, and the elastic part in the form of a thick facing of soft leather, indicated at 18, cemented to a transversely disposed rounded channel or concavity on the face of the head body 8'; the latter being secured to the flange 14, by suitable means such as by screws as shown. The channeled or concaved form of the face 18 of the contact head and its lining best illustrated in Fig. 5 is of special value in making sliding contact with the curved surface of the tracker bar of a player piano, and in this form of the contact face the opening 11' (see Fig. 5) may be lengthened to cover several duct openings to be cleaned. Between the cylinder head and the contact head or cap is mounted a check valve, shown in the drawings, Fig. 4, as a flap valve 15 swinging transversely to the direction of the length of the contact head, to open and close the intake opening therein. In a plane slightly below the permitted length of stroke of the piston, in the wall of the cylinder is mounted a dust discharging valvular device, consisting of the tubular member 16 within which is a coiled spring 17 held by a pin 17', the other end being fastened to head end of the member 19. The tubular member 16 is open at both ends, one end being mounted in the wall of the cylinder body and the other end, which is preferably flanged as shown, is normally covered by the tubular member 19 which is closed at its outer end, and is slidingly mounted on the fixed tubular member 16. The slid-

ing member 19 is peripherally perforated by an annular row of perforations 20' which are normally held out of register by the spring and are brought into register by the return stroke of the piston, to discharge the dust which, on the outstroke of the piston has been sucked out of the tubular passages to be cleaned and drawn into the piston cylinder, such stroke of the piston opening the flap valve and closing it on the return stroke. Of course some other form of check valve could be used in the same way and with like results, in place of the flap valve, if preferred.

Having thus described my invention, I claim:

1. A dust-cleaning suction pump of the class described, comprising in combination, a cylinder, piston and piston rod, a suction nozzle, including means to secure it to the cylinder head, said nozzle having a yieldable contact face and an axially-disposed passage leading therefrom directly to the interior of the cylinder; valvular means operable to keep said passage normally closed and to open it by the suction stroke of the piston; and dust-discharging valvular means mounted on the periphery of the cylinder, normally out of communication with the atmosphere and operable to be opened by the return stroke of the piston to discharge the cylinder contents.

2. A dust-cleaning suction pump of the class described, comprising in combination, a cylinder, having a hollow nipple on its head end, a piston and piston rod, a suction nozzle, having a yieldable contact face, a recess on its under face adapted to register with and be secured thereby to said nipple and an axially-disposed passage leading therefrom directly to the interior of the cylinder; valvular means operable to keep said passage normally closed and to open it by the suction stroke of the piston; and dust-discharging valvular means mounted on the periphery of the cylinder, normally out of communication with the atmosphere and operable to be opened by the return stroke of the piston to discharge the cylinder contents.

3. In a dust-cleaning suction pump of the class described, comprising in combination, a cylinder, piston and piston rod, said cylinder including a suitable suction nozzle thereon, having an axially disposed passage leading directly to the interior of the cylinder; valvular means normally closing said passage and operable to open it by the suction stroke of the piston; and dust-discharging valvular means normally out of communication with the atmosphere and operable only on the return stroke of the piston, said means comprising an open-ended tubular member fixedly mounted by one end in the peripheral wall of the cylinder, adja-

cent to the first mentioned valvular means, a tubular cap member sleeved on said fixed tubular member and slidable thereon, and a spring between said members operating to normally maintain them in relatively closed position, said sliding member being annularly perforated and movable by air pressure to open communication with the atmosphere.

10 4. In a dust-cleaning suction pump of the class described, comprising in combination, a cylinder, piston and piston rod, a suction nozzle on the cylinder head, said nozzle having a yieldable contact face and an axially disposed passage leading directly to the interior of the cylinder; valvular means operable to keep said passage normally closed and to open it by the suction stroke of the piston; and dust-discharging valvular means comprising a fixed tubular member having an exterior annular flange, said member communicating directly with the interior of the cylinder, a slidable tubular member closed at one end and mounted sleeve-like on said fixed tubular member in manner to normally close the free end thereof, a spring between said tubular members operating to maintain them in relatively closed position, said sliding member being annularly perforated and movable on the fixed member by the return stroke of the piston to open communication with the atmosphere.

15 5. In a dust-cleaning suction pump of the class described, comprising in combination, a cylinder, piston and piston rod, a suction nozzle on the cylinder head, said nozzle having a yieldable contact face and an axially disposed passage leading directly to the interior of the cylinder; valvular means adapted to normally close said passage and operable to open it by the suction stroke of the piston; and dust-discharging valvular means communicating directly with the interior of the cylinder but normally out of communication with the atmosphere, said means comprising an open-ended tubular member fixedly mounted by one end in the peripheral wall of the cylinder adjacent to the first mentioned valvular means, a tubular cap member sleeved on said fixed tubular member and slidable thereon, and a spring between said tubular members operating to normally maintain them in relatively closed position, said sliding member being annularly perforated and movable by

20

25

30

air pressure to open communication with the atmosphere.

5. In a dust-cleaning suction pump of the class described, comprising in combination, a cylinder, piston and piston rod, a suction nozzle on the cylinder head, said nozzle having a yieldable contact face and an axially disposed passage leading directly to the interior of the cylinder; valvular means operable to keep said passage normally closed and to open it by the suction stroke of the piston; and dust-discharging valvular means comprising a fixed tubular member having an exterior annular flange, said member communicating directly with the interior of the cylinder, a slidable tubular member closed at one end and mounted sleeve-like on said fixed tubular member in manner to normally close the free end thereof, a spring between said tubular members operating to maintain them in relatively closed position, said sliding member being annularly perforated and movable on the fixed member by the return stroke of the piston to open communication with the atmosphere.

In testimony whereof, I have hereunto affixed my signature this twenty seventh day of March A. D. 1919.
